2 SHEETS-SHEET 2.

UNITED STATES PATENT OFFICE.

JOHN H. HOTSON, OF BROOKLYN, NEW YORK, ASSIGNOR TO TYPEWRITER SPEED KEY COMPANY, A CORPORATION OF NEW YORK.

KEYBOARD.

1,146,570.

Specification of Letters Patent. Patented July 13, 1915.

Application filed November 5, 1912. Serial No. 728,703.

To all whom it may concern:

Be it known that I, JOHN H. HOTSON, a citizen of the United States, and a resident of Brooklyn, in the county of Kings and State of New York, have invented certain new and useful Improvements Relating to Keyboards, of which the following is a specification.

This invention relates to keyboards for typewriters, adding machines, and the like, and the various features of construction and operation included therein are designed more especially for embodiment in attachable or auxiliary keys adapted to be applied to or removed from the regular key buttons forming part of the machine, the general object of the invention being to increase the speed, certainty and ease of writing and to guard against injury to the fingers.

20 A special object is to provide auxiliary keys having simple and secure fastening means whereby they may be easily sprung on and off ordinary or regular key buttons.

25 A further object is to provide a novel and advantageous assemblage of clamp or supporting member, cap, and interposed spring cushion and guiding and connecting members. Another object is to provide a simple structure for guarding the cushion spring, 30 and guiding members and for deflecting misdirected finger blows.

Still another object is to provide a cap with a separate extension piece, or with an extension of different material or appearance, and preferably with one that may be applied to or removed from the cap or reversed in position, constituting an attachable and detachable extension of the striking surface.

40 These and other objects are attained by the key constructions hereinafter described in their preferred embodiments in connection with the accompanying drawings wherein such preferred embodiments are illustrated.

45 In these drawings, Figure 1 is a plan view of part of a keyboard embodying the features of the invention; Fig. 2 is a side elevation of the same; Fig. 3 is a vertical longitudinal section through one of the attachable keys, showing it applied to a permanent key in elevation; Fig. 4 is a vertical transverse section of the same, on the line 4-4 of Fig. 3; Fig. 5 is a sectional side elevation show-

ing one of these keys being applied; Fig. 6 55 is a horizontal section on the line 6-6 of Fig. 3, looking down; Fig. 7 is a horizontal section on the line 6-6 of Fig. 3, looking up; Fig. 8 is a vertical longitudinal section through another of the keys; Fig. 9 is a horizontal section on the line 9-9 of Fig. 3; Fig. 10 is a vertical section on the line 10-10 of Fig. 9; Fig. 11 is a schematic view showing a curved reinforce plate about to be secured in the clamp or attaching shell 65 by means of pressure to flatten the plate; Fig. 12 is a similar view showing the operation completed; Fig. 13 is a horizontal section on the line 13-13 of Fig. 12, and Fig. 14 is a side elevation showing a different 70 embodiment of certain features of the invention.

The invention is shown applied to a typewriter keyboard having four rows of keys, though it is not limited to this form of keyboard. The keys *a* of the first row are provided with extensions 10 at the front, the keys *b* of the second row are without extensions, the keys *c* of the third row are provided with extensions 10 at the back, and the 80 keys *d* of the fourth row are without extensions but are provided with skirts 11 herein-after more fully described, which prevent the fingers when aimed at the keys of the third row striking the supporting springs 85 of the keys of the last row and deflect such misdirected blows forward and downward onto the third row keys. While this is the preferred arrangement of the keyboard, it will be understood that extensions such as 90 10 may be applied to any keys, either at the front or back, where it may be deemed desirable to have additional striking surface, and that keys other than those of the back row may be provided with the skirts 11. 95

With the exception of the extensions 10 and the skirts 11 the construction of all the keys is preferably similar. They comprise clamps 12 constructed so as to be sprung on and off regular key buttons, such as shown at 100 13, caps 14 yieldable bodily relatively to the clamps, a cushion spring 15 interposed in the space between the clamp and cap, and guiding and retaining pins or studs 16.

The clamp 12 is made of sheet metal and 105 constitutes a cover for the key button on which it is placed. As shown it comprises a circular top or disk and downward pro-

jecting spring means to grip or snap under the sides of the permanent key button 13, the said means preferably consisting of claws 17 and 18 at front and back, there being two of each and the front claws being preferably shorter than the back claws and turned in, whereas the lower portions of the back claws flare out, as shown at 19. It is desirable to make the front claws 17 just long enough so that their tip ends project below and slightly under the bottom edge of the permanent key button. The back claws 18 curve in and then flare out at their lower portions as just described, the innermost or holding portions of these claws being located so as to come just under the bottom edge of the key button. In addition to these holding devices, the top of the clamp is provided with shallow downward projecting circular side walls 20 which receive the sides of the key button and assist in properly locating the auxiliary key on the permanent key.

The top of the clamp is provided with a marginal shoulder 21 forming a seat which rests on top of the key button 13 or the raised rim thereof and serves to elevate the central portion 22 of the top, so that between it and the depressed surface of the permanent key button an adequate chamber is formed to permit the play of the heads of the pins 16. If the surface of the permanent key button is flush the distance of the shoulder 21 below the top of the clamp, or in other words the height of the elevated portion of the top, may be increased.

In order to facilitate the springing on of the clamp it is provided beneath and at the margin with a cavity to admit the upper edge of the permanent key button when the clamp is applied by a tilting action, as indicated in Fig. 5. This cavity is shown formed by interrupting the shoulder 21 at one point, the resulting recess enlargement, designated 23, being located adjacent the short hooked front claws 17. Thus, in applying the clamp the forward part thereof is first placed against the forward edge of the key button and the clamp is then swung downward until the back claws 18 snap over the back of the permanent key button and the top is horizontal. The cavity 23 renders this operation convenient by enabling the back claws to reach farther over the back of the permanent button during the tilting movement, thus decreasing the force that need be exerted and reducing the strain on the clamp. When the clamp is seated the cavity has no effect upon the holding.

The clamp as just described can be made cheaply by simple die operations by using the proper grade of sheet metal, but the metal feasible for this purpose does not possess the proper qualities for a spring clamp which is to be repeatedly sprung on

and off the key buttons and is required to hold firmly when in place. I have discovered, however, that the holding claws may be given the requisite elasticity by forming them with short vertical or longitudinal ribs or corrugations 24, in the basal or upper portions of the claws, that is to say, above their innermost points.

The top of the clamp is reinforced by a plate or disk 25, which in this instance occupies the upper part of the recess beneath the top formed by the raised portion 22. This reinforcing plate is held in place in a novel manner by having its peripheral portion or oppositely projecting lugs 26 forced into the side walls 27 of this recess, as shown in Fig. 13. The method of assembling these two parts is indicated in Figs. 11 and 12. The reinforcing plate is introduced into the recess, or the clamp with the recess is placed over it (which is the same thing), the plate 25 being in curved or bowed condition, which decreases the maximum width of the disk sufficiently to be received in the recess. That is to say, the size of the disk is such that its lugs would prevent it being placed in the recess if flat. Consequently by flattening the reinforcing plate in the recess, as by means of a suitable bed member 28 and a plunger or hammer 29, the lugs 26 are forced endwise into the walls 27, being thus held in place with exceptional firmness and without special fastening means.

Registering openings 30 are formed in the portion 22 of the top of the clamp and in the reinforcing plate 25. They may be made by the same operation and mechanism that force the plate into holding engagement with the top of the clamp. In these openings the pins 16 are guided, the said pins being provided at their lower ends with heads or stops 31, which contact with the reinforcing plate. The pins are preferably spaced fore and aft and are located at opposite sides of the center of the clamp. On the upper ends of the pins is solidly driven a plug 32 of fiber or other suitable material forming the body of the cap 14. The pins thus constitute plungers projecting downward from the cap. The said plug is enclosed at top and sides by a suitable covering or casing 33, which may be a celluloid cup or a metal cup covered with celluloid, or of other suitable material and construction, and suitably secured to the plug. The top of the covering bears the marks indicating the characters operated by the keys.

Between the cap 14 and clamp 13 is interposed the spring 15, which is preferably an approximately S-shaped spring such as is disclosed and claimed in my prior application, Serial No. 533,521, filed Dec. 17, 1909. It is made of flat stock bent to present approximately horizontal loops one above the other and reversely disposed, the loops rang-

ing fore and aft. When the plug 32 is driven onto the upper ends of the pins 16 it places the spring under compression, so that the cap is firmly yet yieldingly supported. 3 As set forth in the aforesaid application, the spring is more yielding at one side of the transverse center line than the other. This may be effected in a variety of ways, one of which is described in the said application. 10 In the present instance one of the bends 34, 35 may be made stiffer than the other by hitting the bend a blow. This differential yielding of the spring at front and back compensates for any tilting of the key in its 15 downward excursion. In the case of key levers pivoted at their rear ends, the weaker part of the spring is at the front, so that the top of the cap 14 may remain substantially horizontal irrespective of the angular movement of its support. The guide pins 16 have sufficient play in their openings 30 to permit the relative angular movement. In the construction shown the key levers may be assumed to be pivoted at their rear ends, and 20 this being the case, the bend 34 is weaker and the bend 35 stiffer, so that the cap tends to tilt to the rear under a finger blow, this tilting of the cap relatively to the key lever compensating for the reverse tilting due to 25 the angular movement of the lever. In the case of machines whose construction is such that the keys tilt naturally toward the rear, the spring is arranged so as to counteract this tilt by enabling the key cap to tilt forward to the proper extent relatively to its support. The spring is held in place and kept from turning by the pins 16, which preferably pass through vertically alined 30 openings 36 in the several members of the spring. The pins, it will be observed, also hold the cap against turning, as well as holding it from lateral displacement and acting as tension members to limit its upward movement under the action of the 35 spring.

The extensions 10 of the first and third row keys are separate from the caps 14 and are provided with means whereby they may be applied and removed by the operator. 50 Furthermore, they are preferably of metal, contrasting with the celluloid or other suitable material constituting the surface of the cap. I have heretofore employed extensions for the purpose of affording added striking 55 surface so as to lessen the chance of errors, but these extensions have formed permanent parts of the key caps and have been of the same material and appearance. The advantages of the present kind of extension 60 are numerous. In the first place the keys provided with them retain the appearance of ordinary keys, thereby avoiding arousing the prejudice of naturally conservative persons. In other words, they give the key- 65 board a heavier and less unusual appearance.

Furthermore, while extended key caps have been demonstrated to be of decided value when the operator becomes accustomed to them, it naturally happens that some operators are hampered at first by the change 70 from regular keyboards; and in this event the removability of the extensions enables part or all of them to be taken off when work must be gotten out and to be replaced when the operator has time to practice until 75 she becomes more proficient with the extended keys than with keys of ordinary form. Then too, in applying the attachable keyboard to some old machines in which some of the regular keys do not stand properly it is found that one or more of the extensions interfere either with the space bar or with the fourth row keys. In this event the extensions which encounter this trouble may be removed, leaving the caps 14 perfect 80 and complete. The same may be true of some machines in which the space bar stands abnormally high. In some makes of machines extra characters usually placed in the first or third row may be found in the second or fourth row, which have been illustrated as unprovided with extensions; and if this is the case the extension may be removed from such character so that it conforms with the rest of the row. Or a character may be found either in the first or third row. In this case the removable extension may be applied either at the front or back as the case may be. Another great advantage of separate extensions is the cheapening of manufacture by enabling the caps proper to be made circular. 90

The specific construction of the separate extensions may be varied. The preferred embodiment will now be described. It is 105 made of one piece of sheet metal bent to present a tongue 37, insertible beneath the cap 14 to hold the extension piece in place, a bottom wall 38 extended forward from the tongue, and a top wall 39 connected with 110 the outer end of the bottom wall by a bent-up end wall 40. The inner edge of the said top wall is incurved to conform to the side of the cap 14 against which it bears. The end wall 40 and the bends connecting it with 115 the top and bottom walls are preferably curved, also. The bottom wall 38 is preferably connected with the tongue 37 by a jog or upwardly bent offset 41, which raises the bottom of the extension above the plane 120 of the bottom of the cap. This provides for a comparatively thin extension, thus affording sufficient clearance to prevent it contacting with the space bar. The top wall 39 is substantially flush with the top of the 125 cap and forms an extension of the striking surface. Pieces 42 may be bent downward from the outer end of the top wall 39 to adjoin the end wall 40 and form side walls continuous therewith. The front end of the 130

extension is preferably provided with an offset 50 at the under side, so as to afford a purchase for the finger in removing the extension piece.

5 The tongue 37 is slotted as shown at 43 so that the resulting bifurcation may embrace the pins 16, which keep the extension from turning. The slot is preferably constricted near its mouth, as shown at 44, so 10 that the members of the tongue must be forced apart slightly in order to pass the pins, this constriction serving to lock the tongue yieldingly against withdrawal. The tongue is also held frictionally between the 15 spring 15 and the cap 14. To support it rigidly against being tilted downward, the cap is provided with a lip 45, which is received in the slot 43 and underlies the portion of the tongue at the closed end of the 20 slot. This tongue may also constitute the means limiting the inward movement of the tongue. As shown, the cap is provided with two of these lips 45, at front and back, respectively, so that the extension piece may 25 be applied in either position. These lips are preferably formed on a metal disk 46 which is held against the bottom of the plug 32 by suitable means, as by being forced onto the pins 16 with a driving fit. The tongue is 30 further held against withdrawal by protuberances or small bosses 47 formed on the top member of the spring 15 and openings or sockets 48 in the two members of the tongue. This construction affords a secure 35 but yielding lock. Either this form of yielding locking means or the constriction 44 may be dispensed with, or they may be used in conjunction.

The protuberances 47 on the top member 40 of the spring are made of substantially the same height as the thickness of the tongue 37, so that when the protuberances are snapped into place in the openings in the tongue, said protuberances almost touch the 45 bottom of the cap, but not quite, because it is desirable to have the tongue clasped resiliently between the spring and cap. When the extension is removed or is not used, the protuberances bear against the bottom of the 50 cap and act as distance pieces. Thus, the presence or absence of the spring makes substantially no difference on the condition or 55 tension of the spring, since the removal of the tongue causes the spring to expand either inappreciably or not at all.

The skirts 11, which may be provided in part or all of the keys, may be formed and held in place in different ways, but the most simple and advantageous construction is one 60 in which they form the sides of inverted cupped shells, the tops of which are provided with openings loosely receiving the pins 16. The said tops are located between the tops of the springs 15 and the undersides 65 of the caps 14, and move up and down with

the latter. Obviously the tops of the said shells might be fixed to the pins or to the undersides of the caps, but this is unnecessary as they are held up against the caps by the pressure of the springs. The skirts in 70 close the springs 15 and prevent the fingers of the operator striking against the same, and their lower edges are sufficiently far above the tops of the clamps 12 not to limit the downward movement of the caps relatively to the clamps. The skirts are flared, or sloped steeply downward and forward, at the front, and the flare preferably decreases at the sides. The back portions of the skirts may be vertical. The steep forward slope 80 serves to deflect any misdirected finger blows intended for the third row keys forward and downward to the proper keys, without actuating the keys carrying the skirts. This result is due to the steepness 85 of the slope which renders the component of the force of any misdirected blow acting on the back row key very small.

In certain of its aspects the invention is not limited to an attachable key or to the 90 use of a clamp such as 12. Fig. 14 illustrates a permanent key construction embodying several features of the invention. 95 51 indicates a key lever, the forward part of which is suitably formed to permit the pins 95 16 to work up and down. These pins are headed at their lower ends and at their upper ends are secured to the cap 14. The spring 15 is interposed between the key lever and cap. The cap is shown with a removable 100 extension piece 10 applied thereto.

While I have described the various features of my keyboard with considerable particularity, it will be understood that various changes may be made without essentially 105 altering the invention.

What is claimed as new is:

1. An attachable key, comprising a clamp formed so as to be applied to a regular key button, said clamp having resilient claws 110 adapted to snap beneath the key button, a cap, a spring on which said cap is yieldingly supported, said spring being between the clamp and cap, and means for limiting the upward movement of said cap relatively to the clamp and normally holding said spring under compression. 115

2. An attachable key, comprising a clamp constructed so as to be sprung on and off a regular key button, a cap separate from and carried by said clamp, a spring separate from said clamp interposed between the clamp and cap as a yielding support for the latter, and means placing the spring under compression and holding the parts against separation. 120

3. An attachable key, comprising a clamp constructed so as to be sprung on and off a regular key button, a cap, a spring separate from said clamp and cap and interposed as 125 130

a yielding thrust connection between the two, and means for guiding the cap and limiting its upward movement.

4. An attachable key, comprising a clamp 5 constructed so as to be sprung on and off a regular key button, a cap, a spring interposed as a yielding thrust connection between said clamp and cap, and pins guiding said cap, keeping it from turning and limiting its upward movement.

5. An attachable key, comprising a clamp 15 constructed so as to be sprung on and off a regular key button, a cap having a plunger guided in the top of the clamp, and a resilient cushion supporting said cap.

6. An attachable key, comprising a clamp 20 constructed so as to be sprung on and off a regular key button, a cap yieldable relatively to the clamp under the finger stroke, guide pins spaced fore and aft, and a spring constituting a yielding support for said cap.

7. An attachable key, comprising a clamp 25 constructed so as to be sprung on and off a regular key button, a cap, guide pins fixed to the cap and working in openings in the clamp, said pins being headed at their lower ends, and a spring interposed between the cap and clamp.

8. An attachable key, comprising a clamp 30 constructed so as to be sprung on and off a regular key button, and having provision whereby its top is elevated, a cap, a spring interposed between the cap and clamp, and a pin fixed to the cap and working in an opening in the elevated top of the clamp, said pin being provided beneath said top with a retaining enlargement.

9. An attachable key, comprising a clamp 35 constructed so as to be sprung on and off a regular key button, a cap, a headed pin passed loosely upward through an opening in the clamp and having its upper end driven into the cap, and a spring interposed between the cap and clamp.

45 10. An attachable key, comprising a clamp constructed so as to be sprung on and off a regular key button, a cap comprising a plug and a covering therefor, a headed pin passed loosely upward through an opening in the clamp and having its upper end driven into said plug, and a spring interposed between the cap and the clamp.

11. An attachable key, comprising a clamp 55 formed of sheet metal and comprising a top to cover a regular key button and downward projecting claws whereby it may be sprung on and off the button, said top having a shoulder forming a seat to rest on the button and elevating the central part of the top, 60 which central part is provided with guide openings, a cap, pins secured thereto and working in said openings, and a spring bearing against the top of the clamp and the under side of the cap.

55 12. An attachable key having a sheet

metal clamp comprising a top to cover a regular key button, side walls to receive the sides thereof, and stiff resilient claws at front and back constructed to enable the clamp to be sprung on and off the button, 70 in combination with a cap and a spring interposed between the cap and clamp and yieldingly supporting the former on the latter.

13. An attachable key having a sheet 75 metal clamp comprising a top to cover a regular key button, side walls to receive the sides thereof, and stiff resilient claws at front and back constructed to enable the clamp to be sprung on and off the button, 80 said claws being bent inward sufficiently to snap beneath the button and one set of claws being longer than the other and having their extremities curved outward so as to facilitate the application of the clamp to 85 the button.

14. An attachable key having a sheet metal clamp comprising a cover for a regular key button having spring means to grip the sides thereof and a marginal shoulder 90 which forms a seat and is interrupted at one point by a recess enlargement facilitating the springing on of the clamp by a tilting action.

15. An attachable key having a sheet 95 metal clamp comprising a cover for a regular key button having spring means to embrace the sides thereof and a cavity in its top at the margin to admit the edge of said button in springing the clamp thereon with 100 a tilting action.

16. An attachable key having a sheet metal clamp comprising a cover for a regular key button having sets of downward projecting claws at front and back to embrace the button, and a cavity in its top adjacent one set of claws to admit the edge of the button in springing the clamp thereon with a tilting action.

17. An attachable key having a sheet 110 metal clamp adapted to be forced downward onto a regular key button, having downward-projecting spring claws at front and back formed with longitudinal ribs.

18. An attachable key, comprising a sheet 115 metal cover for a regular key button having spring means to grip the sides thereof, and a reinforcing plate beneath the top of said cover and having peripheral portions forced into the sides thereof, said plate and the top of the cover having registering openings, in combination with a pin headed at its lower end passed loosely upward through said openings, a cap fixed to the upper end of said pin, and a spring interposed between 125 said cover and cap.

19. An attachable key, comprising a sheet 130 metal clamp for attachment to a regular key button having spring means to grip the sides thereof and a top formed with a raised por-

- tion affording a recess, a reinforcing plate in said recess, in combination with a pin headed at its lower end passed loosely upward through said reinforcing plate and 5 raised portion, a cap fixed to the upper end of said pin, and a spring interposed between said cover and cap.
20. An attachable key, comprising a clamp constructed so as to be sprung on and off a regular key button, a cap, an S-shaped spring between said clamp and cap, and a guide pin connecting said clamp and cap for relative movement and passing through said spring.
- 15 21. An attachable key, comprising a clamp constructed so as to be sprung on and off a regular key button, a cap, a spring between said clamp and cap, and spaced guide pins connecting said cap and clamp for relative movement and holding said spring against turning.
22. An attachable key, comprising a clamp constructed so as to be sprung on and off a regular key button, a cap, a spring between said cap and clamp more yielding at one side of the transverse center than the other, and spaced guide pins connecting said cap and clamp for relative movement and holding said spring against turning.
- 30 23. An attachable key, comprising a clamp constructed so as to be sprung on and off a regular key button, a cap, a spring between the cap and clamp, a pin connecting the cap and clamp and permitting relative movement thereof, and a skirt inclosing said spring and pin.
24. An attachable key, comprising a clamp constructed so as to be sprung on and off a regular key button, a cap, a spring between the cap and clamp, guide pins connecting the cap and clamp for relative movement, and a shell having a top beneath said cap and a skirt inclosing said pins and spring.
- 45 25. In a key, the combination of a support forming part of the key, a cap, a spring interposed between said support and the cap, and a skirt depending from said cap and flaring at the front to deflect misdirected finger blows.
- 50 26. An attachable key, comprising a clamp constructed so as to be sprung on and off a regular key button, a cap, a spring between the cap and clamp forming a yielding support for the former, and a shield movable with the cap and guarding said spring, said shield being inclined steeply downward and forward so as to deflect misdirected finger blows.
- 55 27. In a key, the combination of a movable supporting member forming part of the key, a cap yieldable relatively to said member, a pin fixed to one of said parts and working in the other, and a cushion spring between said member and cap held in place 65 by said pin.
28. In a key, the combination of a movable supporting member forming part of the key, a cap yieldable relatively to said member, guide pins spaced fore and aft, said pins 70 being secured to one of said parts and operating in openings in the other, and a spring interposed as a yielding thrust connection between said cap and member.
29. In a key, the combination of a movable supporting member forming a part of the key, a cap yieldable relatively to said member, an approximately S-shaped spring 75 interposed as a resilient thrust connection between said cap and member with its loops 80 disposed fore and aft, and guide pins spaced fore and aft and passing through said spring.
30. In a key, the combination of a movable supporting member forming part of the key, a cap yieldable relatively to said member, pins fixed to one of said parts and working in openings in the other, said pins being provided with heads preventing separation of the parts, and a spring interposed as a cushion between said member and cap, said spring being formed of flat stock bent to present loops one above the other ranging fore and aft and provided with openings 90 through which said pins pass.
31. A key cap having a separate attachable and detachable horizontal extension of its striking surface, said extension being substantially in the plane of the top of the key cap.
32. A key cap having a circular top and a horizontal extension of its striking surface of different material from said circular top, said extension being substantially in the plane of the top of the key cap.
33. The combination of a key cap having pins projecting downward therefrom, and an extension piece affording an extension of the striking surface of the cap and having a tongue inserted beneath the cap and provided with a slot to receive said pins.
34. The combination of a key cap having pins projecting downward therefrom, and an extension piece affording an extension of the striking surface of the cap and having a tongue insertible beneath the cap and provided with a slot to receive said pins, said slot being constricted at one point so as to yield in being forced onto the pins and to hold the tongue against withdrawal.
35. The combination of a key cap, an extension piece having a slotted tongue inserted beneath said cap, and means beneath the cap received in the slot in said tongue to hold it in place including a lip which underlies and supports the tongue at the rear end of the slot.
36. In a key the combination of a sup-

porting member, a cap, a cushion spring between the supporting member and cap, an extension piece having a tongue insertible between the top of the spring and the under-
5 side of the cap, said tongue and the top of the spring being provided with protuberances and sockets constituting yielding locking means.

37. In a key, the combination with a sup-
10 porting member, a cap, and a cushion spring between the supporting member and cap, of an attachable and detachable extension piece held between said spring and cap.

38. In a key, the combination with a sup-
15 porting member, a cap, a cushion spring between said member and cap, spaced fore and aft guide pins connecting said cap and member for relative movement, and an extension piece having a tongue held between said
20 spring and cap and provided with a slot receiving said pins which keep it from turning.

39. The combination of a key cap, an extension piece constituting an extension of the striking surface of the cap, and means
25 for attaching said extension piece at either the front or the back of the same cap.

40. The combination of a key cap, an extension piece affording an extension of the striking surface of the cap, and a tongue

supporting the extension piece and held beneath the cap. 30

41. An extension piece for key caps formed of one piece of sheet metal bent to present a top having its inner edge formed to fit the side of the cap, the metal being bent downward at the outer end of the top, then in-
35 ward and extended to form a tongue adapted to underlie the cap.

42. An extension piece for key caps formed of one piece of sheet metal bent to present a 40 tongue adapted to underlie the cap, a bottom wall connected with said tongue by a jog whereby the bottom of the extension is ele-
45 vated above the bottom of the cap, and a top wall continuous with the outer end of said bottom wall and having its inner edge formed to fit against the side of the cap.

43. The combination with a key cap, of an attachable and detachable extension piece of less depth than the cap and having an at-
50 taching tongue underlying the cap and offset downward from the bottom of the extension.

In witness whereof I have signed my name in the presence of two subscribing witnesses.

JOHN H. HOTSON.
